UNITED STATES PATENT OFFICE

109,553

DESIGN FOR A TRAVELING BAG

Charles Doppelt, Chicago, Ill.

Application March 10, 1938, Serial No. 75,729

Term of patent 14 years

To all whom it may concern:

Be it known that I, Charles Doppelt, a citizen of the United States, residing at Chicago, and the county of Cook and State of Illinois, have invented a new, original, and ornamental Design for a Traveling Bag, of which the following is a specification, reference being had to the accompanying drawing, forming part thereof.

Figure 1 is a perspective view of a traveling bag showing my new design in closed position.

I claim:

The ornamental design for a traveling bag, as shown and described.

CHARLES DOPPELT.
